(57) **CLAIM**

The ornamental design for a watch dial as shown and described.

DESCRIPTION

FIG. 1 is a top view of a watch dial of my present design; FIG. 2 is a bottom view thereof; FIG. 3 is a right side view thereof; FIG. 4 is a left side view thereof; FIG. 5 is a front view thereof; FIG. 6 is a rear view thereof; and FIG. 7 is a top right perspective view thereof; and, FIG. 8 is a bottom left perspective view thereof.

The broken lines in the drawings depict structures or features of the watch dial that form no part of the claimed design and are included to show the context in which the design exists.
